UNITED STATES PATENT OFFICE.

HERMANN BORMANN, OF PHILADELPHIA, PENNSYLVANIA, ASSIGNOR, BY
MESNE ASSIGNMENTS, TO J. WALTER DOUGLASS, OF SAME PLACE.

APPARATUS FOR MAKING ROOFING FABRICS.

SPECIFICATION forming part of Letters Patent No. 427,147, dated May 6, 1890.

Application filed December 6, 1889. Serial No. 332,744. (No model.)

To all whom it may concern:

Be it known that I, HERMANN BORMANN, a subject of the Emperor of Germany, but now residing at the city of Philadelphia, in the county of Philadelphia and State of Pennsylvania, have invented certain new and useful Improvements in Apparatus for Making Roofing Fabrics, of which the following is a specification.

10 My invention relates to the manufacture of a silica-coated two or more ply roofing fabric provided with a marginal edge or edges.

Heretofore roofing fabrics composed of felt or paper have generally been prepared by first 15 coating the entire surface of the sheet of felt or paper with tar or pitch or permitting the tar or pitch to permeate the body thereof, and then applying to the under side a sheet of burlap or other somewhat similar material 20 and to the upper surface a coating of sand after the saturated or tar-coated sheet had become more or less cool; but one of the most serious objections experienced in the use of such fabrics has been the difficulty of securing 25 in the uniting of one sheet to another a perfectly-tight joint.

The principal object of my invention is to provide apparatus of comparatively simple construction, and in which the arrangement 30 of the parts is such that either two, three, or more ply fabrics with uncoated marginal sides or edges may be economically obtained for roofing and other similar purposes, and of such character as to enable one sheet to be 35 readily united to another to form perfect water-tight joints and an even and smooth roof both in appearance and in fact.

My invention consists of the novel arrangement of apparatus for obtaining a two or more 40 ply marginal-edged silica-coated roofing fabric, and such apparatus having relation, first, to the mode of applying to or saturating felt or paper with tar, pitch, or other somewhat analogous material or substances, and, second, to the mode of applying to the tarred or 45 saturated fabric a silica and allowing the same to become firmly embedded therein adjacent to the marginal edge or edges, which are maintained intact or free from pitch, tar, 50 or other substances.

The nature and characteristic features of my invention will be more fully understood from the following description, taken in connection with the accompanying drawings, forming part hereof, and in which—

55

Figure 1 is a vertical longitudinal section through a plant embodying the features of my invention, and especially adapted for making a two-ply marginal-edged silica-coated roofing fabric. Fig. 2 is a top or plan view thereof. Fig. 3 is a vertical longitudinal section through an organized plant embodying the features of my invention, and especially adapted for making a three-ply roofing fabric. Fig. 4 is a top or plan view 60 thereof; and Fig. 5 is a detail view of one of the sectional or recessed coating-rollers partially immersed in a vat containing hot tar, pitch, or other material for coating one surface of a sheet of felt or paper.

70

Referring to the drawings for a further description of my invention, A is a furnace having a grate a in the lower part thereof. Above the grate a is provided a chamber a', within which is supported a tank B, adapted to contain tar, pitch, or other material to be melted or heated for use. C is the draft pipe or flue connected with the chamber a', and extending beneath a frame or rack D and upward adjacent to a hopper E, as hereinafter more 75

fully described.

One end of the frame or rack D, Figs. 1 and 2, is mounted on and rests against the top of the furnace A. The lower longitudinal tie-piece or stringer d of said frame or rack D is 80 provided with a roller F, adapted to contain a sheet of felt or paper 1. Guide-rollers f and f' are arranged on opposite sides of a vat g, suspended from said tie-pieces d into the tank B, and adapted to permit of heated tar or 85 pitch being introduced therein. Above the vat g, and journaled to said longitudinal pieces d, is a plain-surfaced roller G, one portion of which extends partially into said vat. The roller G is adapted to coat the under side 90 of the sheet of felt or paper 1, caused to pass from the roller F over the guide-roller f, and after said sheet of felt or paper is coated by its passage over the roller G, the sheet is 95 caused to pass under the guide-roller f', ad- 100

jaçent thereto, and the end of said sheet of felt or paper 1 is then united with the end of a similar sheet of felt or paper 2 wound around the roller H, from whence the two united 5 sheets of felt or paper with the coating of hot tar or pitch between them are conducted downward under the flanged guide-roller i, and thence over a sectional or recessed coating-roller I, partially immersed in a vat h 10 containing hot tar or pitch and suspended from the tie-piece d, coating the under side or surface of the two united sheets, whence they pass under the flanged guide-roller i', and thence pass upward and along over a series 15 of plain-surfaced rollers j, journaled to the frame or rack D at suitable distances apart to a point under a pivotally-supported hopper E, provided with a perforated bottom e. The hopper E, containing a silica or other 20 similar material, and capable of being readily reciprocated, deposits the silica onto the tarred upper surface of the united sheets of felt or paper, and is then caused to pass onward between the rollers l and l', whereby 25 the silica becomes firmly fixed to or in the tarred upper surface of the product, and it is then wound around or laid up for use on a roller M, suitably journaled to standards m and m', Fig. 2. This roller M has mounted 30 on one of the journals thereof a crank m² for actuating the same. The tar coated or saturated two-ply fabric is maintained in a heated condition by the waste or draft heat from the furnace passing through the flue C until the silica 35 has been deposited thereon; and the product becoming cool after its passage between the rollers l and l' at the forward extremity of the rack D, the tarred sheets are not only firmly pressed together, but the silica deposited 40 on the tarred upper surface of the sheets is firmly embedded therein lengthwise and contiguous to the marginal edge or edges thereof, while the latter is or are free from the tar or other material. The flanged rollers i and i', 45 disposed on opposite sides of the sectional or recessed coating-roller I, are for the purpose of guiding the united sheets of felt or paper 1 and 2 over the coating-roller I and to insure a marginal edge of the proper or required 50 width being given to the fabric.

In Fig. 3 is illustrated a plant especially adapted to making of a three-ply marginal-edged roofing fabric. In this view, A is the furnace provided with a grate a. a' is a chamber located above said grate and within which is mounted a tank B. C is a draft flue or pipe connected with said furnace and extending along beneath the frame or rack D, and thence upward adjacent to the hopper E. The rack 55 D is provided with a rear extension D', which is mounted on the furnace A, and to which is suitably journaled a roller F, carrying a sheet of felt or paper 1. H is a second roller journaled to the rear extension D' of said rack 60 and carrying a sheet of felt or paper 2. H' is a third roller journaled to said extension D' and carrying a sheet of felt or paper 3. h

is a vat containing hot tar, pitch, or other preferred material. This vat is suspended from the extension D' of the rack D. I is a sectional or recessed coating-roller, one part of which is partially immersed in said vat h, and the other part thereof is located outside of said vat. i and i' are two flanged guide-rollers disposed on opposite sides of said sectional coating-roller I. j' is an upper guide-roller, around which the sheet of felt or paper 3 passes from the flanged guide-roller i' to the roller j', journaled in the rear extremity of the forward extension of the rack D. j are 80 a series of rollers loosely journaled in the standard or rack D, and along over which the united tar-coated sheets of felt or paper 1, 2, and 3 pass from the respective rollers F, H, and H' to and under the hopper E, to receive 85 through the perforated bottom e thereof the deposit of silica or other preferred material, and while maintained in a heated condition by the waste heat passing through the draft flue or pipe C, located underneath or contiguous to said rack D. The three-ply fabric, after receiving the silica from the hopper E capable of being readily reciprocated, is conducted between the rollers l and l' at the forward extremity of the rack D to the roller M, 90 and wound or laid up thereon for use by means of a crank m² attached to one of the journals of said roller. This roller is mounted in suitable standards m and m', as clearly 95 shown in Fig. 4.

The mode of making a two-ply silica-coated roofing fabric with a marginal edge or edges in apparatus of the type illustrated in Figs. 1 and 2 may be explained as follows: A fire is started on the grate a of the furnace A, 105 which heats or melts the tar or pitch contained in the tank B. The vats g and h, suspended from the tie-piece d of the rack D, are then filled with hot tar or pitch, with the coating-roller G and the sectional or recessed 110 coating-roller I partially immersed therein. The felt or paper 1, wound around the roller F, is passed under the guide-roller f, thence over the coating-roller G, partially immersed in the vat g, and under the guide-roller f', 115 whence the sheet, coated on the under side thereof, is united with the end of an uncoated sheet of felt or paper 2, wound around the roller H, whence the two sheets are conducted under the flanged guide-roller i and upward 120 over the coating-roller I, then under the flanged guide-roller i', and then upward over one of a series of rollers j, suitably journaled to the rack D, and thence conducted along over the series of rollers j, to and under the 125 hopper E, actuated in any preferred manner to cause the silica to be deposited on and in the upper coated surface of the united sheets of felt or paper 1 and 2 while maintained in a more or less heated condition by the waste 130 heat from the draft-flue C of the furnace. The fabric, after receiving the silica or other material, is then caused to pass between the rollers l and l' in the front extremity of the

rack D, and laid up in the form of a roll around the roller M, journaled in the standards m and m' , by revolving the crank m^2 in any preferred manner. The flanged rollers 5 i and i' , located on opposite sides of the sectional or recessed coating-roller I, guide the sheet of felt or paper to free the same from the tar, pitch, or other material or substances along the edge or edges thereof on 10 either one or both sides, thereby leaving the fabric with a marginal edge or edges, according to the particular construction and arrangement of the coating-roller I. This coating-roller I may be either recessed on one or 15 both ends, as may be required, and the finished product formed with either a marginal edge on one or both sides of the fabric, extending the entire length thereof.

The mode of making a three-ply silica-coated roofing fabric with a marginal edge or edges in an apparatus of the type illustrated in Figs. 3 and 4 may be explained as follows: A fire is started on the grate a of the furnace A, and when the tank B, containing pitch, tar, or other material, is heated or melted, the vat h is filled with a sufficient quantity of tar or pitch to partially immerse the sectional or recessed coating-roller I therein. The sheet of felt or paper 2, wound 20 around the roller H, is conducted in any preferred manner downward around the roller o , journaled to the standards d^2 of the rear extension D' of the rack D, and thence upward to the roller j^2 at the rear extremity of the 25 forward extension of the rack D, where it is united with the end of the sheet of felt or paper 1 from the roller F. The end of the sheet of felt or paper 3 from the roller H' is then led under the flanged roller i , then over the 30 sectional or recessed coating-roller I, thence downward under the flanged roller i' , and then upward around a roller j' to a point of union with the ends of the sheets 1 and 2 at the roller j^2 . The three united sheets of felt 35 or paper are then conducted along over the series of rollers j , loosely journaled to the rack D, to and under the hopper E, receiving the silica from the same through the perforated bottom e thereof, and from which point 40 the united and silica-coated fabric having a plain-surfaced marginal edge on one or both sides thereof is conducted between the two rollers l and l' at the forward extremity of the rack D, whereby the silica becomes firmly 45 fixed to and embedded in said fabric contiguous to its longitudinal margin or margins. After passing between the rollers l and l' , the fabric is laid up or wound around the roller M, journaled in the standards m and m' , 50 by the actuation of the crank m^2 , mounted on one of the extremities of said roller M.

It will be seen from the arrangement of the apparatus, as shown and described, that the tar coated or saturated fabric is maintained 55 in a more or less heated condition until after the same has received the silica or similar material on the upper coated surface, which

latter adheres more thoroughly than if it had been deposited thereon after the fabric had become partially cold; and, moreover, the method hereinbefore described of making such fabrics is more economical than those heretofore practiced, and the product obtained far superior in many respects—that is to say, a roof composed of sheets of such a fabric 75 may be laid without fear of leaking, as by providing each sheet with a longitudinal marginal edge or edges perfect unions or joints of one sheet with another can be readily made and a smooth and even roof presented 80 without overlapping silica-coated seams or joints, as has been the case in using fabrics as previously made for roofing purposes.

Having thus described the nature and objects of my invention, what I claim as new, 85 and desire to secure by Letters Patent, is—

1. In a plant for making a roofing fabric, the combination of a furnace provided with a chamber, a tank adapted to contain a material or materials to be melted or heated supported therein, a rack supported on and extending beyond said furnace and provided with a series of rollers, a reciprocating hopper, a draft-pipe connected with said furnace and extending beneath said rack and contiguous to said hopper, feed-rollers, plain-surfaced and flanged guide-rollers, and sectional or recessed coating-rollers journaled to said rack, substantially as and for the purposes described: 100

2. In a plant for making a marginal-edged silica-coated roofing fabric, the combination, with a furnace provided with a tank containing a material, a draft flue or pipe located in proximity to a rack provided with rollers, 105 along which the treated material is caused to travel to a laying-up roller, feed-rollers and guide-rollers journaled to said rack, sectional or recessed coating-rollers journaled to said rack and partially immersed in vats containing a material in a heated state, and a reciprocating hopper provided with a perforated bottom located above said rack, substantially as described. 110

3. In a plant for making a marginal-edged silica-coated roofing fabric, the combination of a tank adapted to receive pitch, tar, or other material, feed-rollers arranged to permit of the coating of both sides of the sheet or sheets of felt or paper, a roller adapted to permit of the feeding of a sheet of felt or paper to the under side of said saturated sheet, a feed-roller adapted to permit of the feeding of a sheet to the upper side of said saturated sheet, a sectional or recessed coating-roller for coating the upper surface of the latter sheet adjacent to the marginal edge or edges of said sheet, flanged guide-rollers disposed on opposite sides of said coating roller or rollers, and means to deposit silica or similar material on the upper coated surface of the two or more united sheets, and a reel actuated to lap up the finished fabric, substantially as described. 115
120
125
130

4. In a plant for making a marginal-edged silica-coated roofing fabric, the combination, with a furnace provided with a tank adapted to contain tar, pitch, or other material, a rack provided with a series of rollers journaled thereto, a draft-pipe connected with said furnace and extending beneath said rack, a hopper provided with a perforated bottom, feed and guide rollers journaled to said rack, and

one or more recessed coating-rollers, substantially as and for the purposes described.

In witness whereof I have hereunto set my signature in the presence of two subscribing witnesses.

HERMANN BORMANN.
